UNITED STATES PATENT OFFICE.

ERNST KREISSIG, OF UERDINGEN, GERMANY.

BUFFER FOR RAILROAD CARS.

Application filed September 10, 1923. Serial No. 661,861.

To all whom it may concern:

Be it known that I, ERNST KREISSIG, a citizen of the German Republic, and residing at Uerdingen, Germany, have invented 5 certain new and useful Improvements in Buffers for Railroad Cars, of which the following is a specification.

My invention relates to improvements in buffers for railroad cars, and more particularly in buffers comprising friction members for taking up the shocks and in which balancing means are provided between a pair of buffers provided at the end of a car. The object of the improvements is to 10 provide a buffer in which only the pressure of the spring for returning the friction members into initial position is transmitted to the balancing mechanism, while the pressure caused by friction is transmitted to the body 15 of the truck.

For the purpose of explaining the invention an example embodying the same has been shown in the accompanying drawings, in which the same reference characters have 20 been used in all the views to indicate corresponding parts. In said drawings,

Fig. 1, is an elevation showing one end of a railroad car provided with my improved buffer,

Fig. 2, is a plan view of Fig. 1 partly in section,

Fig. 3, is a sectional view on an enlarged scale showing the buffer, and

Fig. 4, is a cross-section taken on the line 4—4 of Fig. 3.

As is known to those skilled in the art in long railroad cars compensating means are provided between the buffers provided at each end of the car, and in constructions 40 such as are now in use the whole reaction of the buffer is transmitted to the compensating mechanism, resulting in the compensating lever being damaged. Therefore in my improved buffer the pressure caused by 45 the friction members is transmitted to the truck. In the construction shown in the drawings the buffers are connected by a balancing lever *a*, having its fulcrum *b* on a transverse beam of the truck, as is known in the art. The buffer consists of a cylindrical housing *f* secured to the end beam *k* of the car and having a cylindrical member *o* telescopingly mounted thereon. Within 50 the housing *f* there are three friction members *g*, *h*, and *i* in frictional engagement

with the inner wall of the housing *f* and formed internally with beveled faces engaged by the beveled outer faces of members *d*. The friction members are disposed between a pair of disks *c* and *e* formed with 60 conical outer faces engaging the beveled inner faces of the members *g* and *i*. On the disk *c* the ram *p* of the buffer is supported, and the disk *e* bears on a tubular rod *m* bearing with its rear end on a spring *l* confined 65 between disks *r* and *s* and supported on one end of the lever *a*.

The operation of the buffer is as follows: If pressure is exerted on the ram *p* the disk *c* is forced inwardly and the friction members *g*, *h*, and *i* are forced outwardly and 70 into frictional engagement with the inner wall of the housing *f* by the beveled faces of the disks *c* and *e* and the members *d* and the reaction of the spring *l*. Therefore the 75 shock is deadened by friction and most of the reaction is transmitted through the housing *f* to the end beam *k*. Simultaneously the disk *e* is forced inwardly and the pressure acting on the said disk is transmitted to the 80 spring *l* and the compensating lever *a*. By the compression of the spring *l* the power is produced for returning the parts of the buffer into initial positions. By the expansion of the spring *l* the disk *e* is forced outwardly and a spring *t* confined between the 85 disks *c* and *e* forces the disk *c* outwardly. Therefore the friction members are relieved of the axial pressure forcing the same together, so that they are readily shifted into 90 initial position without getting into frictional engagement with the housing *f*.

As the object of the spring *l* is merely to return the friction members into initial positions, and the friction of the said members 95 moving into initial position is small, a comparatively weak spring *l* may be provided. Therefore also the lever *a* may be comparatively weak.

While in describing the invention reference has been made to a particular example embodying the same I wish it to be understood that my invention is not limited to the construction shown in the drawing, and that various changes may be made in the 105 general arrangement of the apparatus and the construction of its parts without departing from the invention.

I claim:

1. In a double buffer system for railway 110

rolling stock the combination with an automatic compensating lever mechanism cooperating with both side buffers, of shock absorbing means within each buffer casing adapted to transmit the buffing shock by frictional resistance to the truck frame, and cushioning means cooperating with said compensating mechanism and adapted to transmit to the latter the fractional amount of the buffing shock not balanced by the shock absorbing means.

2. In a double buffer system for railway rolling stock, the combination with an automatic compensating lever mechanism cooperating with both side buffers, of nested annular wedge-shaped shock absorbing units within each buffer casing adapted to transmit the buffing shock to the truck frame by frictional resistance, and cushioning springs cooperating with said compensating lever and adapted to transmit to the latter the

fractional amount of buffing shock unbalanced by said shock absorbing units.

3. In a double buffer system for railway rolling stock, the combination with an automatic compensating lever mechanism cooperating with both side buffers, of nested annular wedge-shaped shock absorbing units within each buffer casing adapted to transmit the buffing shock to the truck frame by frictional resistance, and cushioning means cooperating with said compensating lever and adapted to transmit to the latter the fractional amount of buffing shock unbalanced by said shock absorbing units, and a releasing spring within said wedge-ring absorbing units adapted to disengage the frictional members for returning the latter into their normal inoperative position.

In testimony whereof I affix my signature

ERNST KREISSIG.
